UNITED STATES PATENT OFFICE.

DAVID W. McLEAN, OF MOUNT VERNON, NEW YORK.

MOISTENING DEVICE FOR DENTAL-ENGINE HANDPIECES.

1,091,522.

Specification of Letters Patent. Patented Mar. 31, 1914.

Application filed December 6, 1913. Serial No. 805,152.

To all whom it may concern:

Be it known that I, DAVID WIELD McLEAN, a citizen of the United States, residing at Mount Vernon, in the county of Westchester 5 and State of New York, have invented a new and useful Moistening Device for Dental-Engine Handpieces, of which the following is a specification.

The present invention appertains to moistening devices for the hand pieces of dental engines, and aims to provide a novel and improved device of that character.

The object of the present invention is to provide a device of the nature indicated, 15 which is in the form of an attachment for the hand piece of a dental engine, and which shall be so constructed, and attachable to a source of water or other liquid, to permit a jet of water to be applied to the 20 grinding disk, bur, drill or other tool carried by the hand piece, whereby the tool may be moistened when applied to the tooth or teeth of the patient, which is highly desirable.

25 It is the object of the present invention to provide an attachment of the character specified, which will be applicable to various hand pieces, the same being attachable to the hand pieces of both foot treadle and 30 electric dental engines.

Another object of the present invention is to provide a novel means for controlling the discharge of water from the attachment, 35 said means being simple, compact, and non-encumbering, and being readily operated by the thumb or fingers of the dentist or operator.

With the foregoing general objects outlined, and with other objects in view, which 40 will be apparent as the nature of the invention is better understood, the present invention resides in the combination and arrangement of parts and in the details of construction hereinafter described and claimed, it 45 being understood that changes in the precise embodiment of the invention herein disclosed can be made within the scope of what is claimed without departing from the spirit of the invention.

50 The invention has been illustrated in its preferred embodiment in the accompanying drawing, wherein:—

Figure 1 is a side elevation of the attachment as applied to the hand piece of a den-

tal engine. Fig. 2 is an enlarged sectional detail of the attachment, illustrating the means for controlling the flow of water therethrough to the nozzle, the section being taken on the line 2—2 of Fig. 3. Fig. 3 is an enlarged end view of the attachment. Fig. 4 is an enlarged sectional detail taken on the line 4—4 of Fig. 1.

In the drawing, the numeral 1 designates a customary or arbitrary hand piece of a foot treadle or electric dental engine, which 65 as illustrated, has the grinding stone or disk 2 applied thereto. It will be apparent, of course, that the grinding disk 2 may be supplanted by a bur or drill, according to the nature of the work to be done. It is the 70 primary function of the present device to moisten the grinding disk or other tool 2.

In carrying out the present invention, there is provided a metallic tube 3 disposed along one side of the hand piece 1, and 75 formed at its end with a tapered valve seat 4, and having its inner or rear end bent angularly to form a nipple 5 for the attachment of one end of the rubber tubing or hose 6 leading to a source of water or fluid supply. 80

A sleeve or barrel 7 is disposed in alignment with the tube 3, and has one end slipped and secured over the forward end of the tube 3, the sleeve 7 being provided with a lateral port 8 adjoining the end of 85 the tube 3. A needle valve 9 is slidably snugly within the sleeve or valve 7 so that its tip co-operates with the valve seat 4 to control the passage of water from the tube 3 through the port or opening 8. The needle 90 valve 9 has a stem 10 slidable through a cap 11 threaded or otherwise engaged with the free or outer end of the sleeve 7, and a coiled wire compression spring 12 is disposed within the sleeve 7 between the cap 11 and the 95 needle valve to yieldably seat the valve.

As a means for opening or unseating the needle valve, a nut or similar member 13 is engaged to the outer extremity of the valve stem 10, and the sleeve 7 is provided with a 100 projection 14 adjoining its free or forward end. An angular lever 15 is pivoted or fulcrumed to the free end of the projection 14 and one arm thereof is provided with a bifurcated opening or slot 16 engaging the 105 valve stem between the nut 13 and the cap 11. The other arm of the lever 15 is formed into a thumb or finger piece 17 extending

along the side of the sleeve 7. By pressing the thumb or finger piece 17 toward or against the sleeve 7, the valve stem will be drawn outwardly against the tension of the 5 spring 12, so as to unseat the needle valve.

A supplemental tube 18 is soldered or otherwise secured to one side of the sleeve 7 and to the end portion of the tube 3, and is provided with the port or branch 19 registering with the port 8 of the sleeve. The 10 free or outer end of the tube 18 is offset slightly away from the free or outer end of the sleeve 7, as at 20, and the free end of the tube 18 is provided with a tapered socket 21 15 for the reception of a flexible metallic nozzle 22. The nozzle 22 may be of any length, and may be bent as desired, so that the tip of the nozzle 22 will properly direct the jet of water against the tool. A number of nozzles 22 may ordinarily be employed in connection with the present attachment, in order that the several nozzles may be interchangeably employed with the attachment, according to the various tools employed, and 20 to meet the various requirements.

In order to conveniently attach the device to various hand pieces, a clip of U-shape is attached rigidly, by soldering or otherwise, to the sleeve 7 and tube 18, as at 23, and an 30 adjustable or slidable U-clip 24 is mounted on the tube 3, the clip 24 having a tubular portion 25 intermediate its ends, snugly embracing the tube 13. Thus, the clip 24 may be slid along the tube 3, and may be swung 35 therearound. The clip 23 is stationary, and may be conveniently applied to the forward end of the hand piece, while the clip 24 may be adjusted as desired, in order to properly engage the inner or rear end portion of the 40 hand piece. In this manner, the device may be applied to various hand pieces, as is highly desirable.

The tubing or hose 6 may be attached to any suitable source of water, such as a special reservoir or container, or may be attached to the service water pipe, to the fountain cuspidor supply pipe, or to the tubing supplying the syringe attachment of the fountain cuspidor.

50. In use, when the attachment is applied to a hand piece, and when water is admitted into the tube 3 through the hose or tubing 6, the needle valve 9 will ordinarily arrest the flow of water. Then, when the engine is in 55 operation, the needle valve may be opened by pressing the thumb or finger piece 17 of the lever 15, which will permit the water to be discharged in a stream from the nozzle 22 against or toward the grinding disk or 60 other tool. As soon as the lever 15 is re-

leased, the spring 12 will seat the needle valve to cut off the flow of water.

From the foregoing, taken in connection with the drawing, the several advantages and uses of the present device will be obvious to those skilled in the art, and need not be further commented upon.

To prevent leakage, it is preferable to dispose a washer or gasket within the cap 11 to embrace the valve stem 10 as seen in 70 Fig. 2.

Having thus described the invention, what is claimed as new is:

1. In a device of the character described, a tube having a valve seat at one end, a 75 sleeve having one end engaged over the said end of the tube and having a lateral port adjoining the end of the tube, a valve slideable in the said sleeve coöperating with the valve seat, and a tube communicating with 80 the said port.

2. In a device of the character described, a tube having a valve seat at one end, a sleeve in alinement with the tube having one end engaged over the said end of the tube, 85 the sleeve having a lateral port adjoining the end of the tube, a valve slideable in the sleeve and coöperable with the valve seat, a cap engaged over the free end of the sleeve, the valve having a stem slideable through the 90 cap, a compression spring disposed between the cap and the valve, means connected to the other end of the valve stem for opening the valve, and a supplemental tube attached to the sleeve and communicating with the 95 said port.

3. In a device of the character described, a tube having a valve seat at one end, a sleeve having one end engaged over the said end of the tube and having a lateral port 100 adjoining the end of the tube, a supplemental tube attached to the sleeve and communicating with the said port, a valve slideable in the tube and coöperable with the seat, the valve having a stem projecting beyond the 105 free end of the sleeve, the sleeve having a projection at its free end, and an angular lever having its elbow fulcrumed to the said projection, one arm of the lever being operatively connected with the valve stem, and 110 the other arm projecting along one side of the sleeve.

In testimony that I claim the foregoing as my own, I have hereto affixed my signature in the presence of two witnesses.

DAVID W. McLEAN.
